PEDESTAL BASE FOR A LIGHT STANDARD

John A. Weaver, R.D. 8, York, Pa.

Filed May 20, 1959, Ser. No. 56,001

Term of patent 3½ years

(Cl. D48—31)

FIG. 3

I claim:

The ornamental design for a pedestal base for a light standard, as shown.
